UNITED STATES PATENT OFFICE.

AXEL H. ENGLUND, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

ELECTRIC SWITCH.

1,244,720.

Specification of Letters Patent. Patented Oct. 30, 1917.

Application filed September 29, 1916. Serial No. 122,821.

To all whom it may concern:

Be it known that I, AXEL H. ENGLUND, a citizen of the United States, residing in the city of Philadelphia, county of Philadelphia, and State of Pennsylvania, have invented an Improved Electric Switch, of which the following is a specification.

My invention is an electric switch designed primarily for controlling the current in a trolley circuit, but it will be understood that it is adapted for general use.

In trolley systems, particularly in mines, it is frequently desirable to open the circuit, or cut out a section, as where the use of a branch is temporarily discontinued, or it is necessary to carry on operations rendered dangerous or inconvenient by the presence of a charged conductor, and my invention provides improved mechanism adapted for such purpose.

My improved mechanism, in its preferred form for use as a trolley cut out, comprises a pair of terminals having means for detachable connection with ends of trolley wire sections and for engaging an oscillatory conductor, a pair of non-conducting bars connecting the terminals, a yoke fixed to the bars, a hanger connected with the yoke, a switch blade fulcrumed by means of the yoke, an arm for rocking the blade, and a spring for holding the blade disengaged from the terminals. It will be understood, however, that the device may be modified, for instance by the means shown for positively locking the blade in its opened relation, and that the invention may be variously embodied within the scope of the claims.

In the accompanying drawings, Figure 1 is a plan view illustrating a form of my invention; Fig. 2 is a side elevation of the construction shown in Fig. 1; Fig. 3 is a sectional view taken on the line 3—3 of Fig. 1; Fig. 4 is a plan view of a section of the device illustrating its combination with disengaged means for positively holding the blade in its open position; Fig. 5 is a view similar to that of Fig. 4 with the blade positively fixed; Fig. 6 is a sectional view taken

on the line 6—6 of Fig. 4; and Fig. 7 is a sectional view taken on the line 7—7 of Fig. 4.

The device, in the form thereof illustrated in the drawings, comprises the terminals 1 and 1' provided with the respective sockets 2 and 2' for receiving the ends of the conductors 3 and 3', and the respective set screws 4 and 4' for fixing such ends in place. The terminals are further provided with the respective pairs of sockets 5 and 5', located on opposite sides of the respective sockets 2 and 2', for receiving the ends of the non-conducting bars 6 and 6' which are fixed in position by screws 7 and 7'.

A yoke 8 is provided with bifurcations 9 and 9' through which the respective bars 6 and 6' pass, the yoke being held on the median sections of the bars by screws 10 and 10'. The yoke is further provided, in its arched top 11, with a socket 12 in which is screwed a hanger or suspension rod 13 for supporting the device, and the bifurcations 9 and 9' are provided with the bearings 14 and 14' in which is journaled the shaft 15. This shaft has the switch blade 16 fixed thereon, between the bifurcations 9 and 9', for connecting the terminals 1 and 1', the latter being provided with the respective "wipes" 17 and 17' for frictionally engaging the respective ends of the blade.

A handle 18, for rocking the shaft 15, is provided with a socket 19 which is engaged on an end of the shaft by a set screw 20. The socket 19 has, on its inner end, a peripheral flange 21 divided by the notches 22; the yoke 8 has, on its bearing 14, a flange 23 provided with a notch 24, and a spring 25, coiled around the shaft 15, has its laterally turned ends 26 and 27 engaged in respective notches 22 and 24. The several notches 22 permit different engagements of the spring's end 26 to vary the tension of the spring, which supplements the weight of the arm 18 and tends to hold the disengaged ends of the blades out of engagement with the "wipes" 17 and 17'.

Binding posts 28 and 28' on the respective terminals adapt them for ready connection

with branch conductors, and eyes 29 and 29' in the terminals provide means for convenient connection of guys.

As illustrated in Figs. 4 to 7 inclusive, the handle 18 contains an aperture 30 through which passes a longitudinally movable bolt 31 having a head 32 adapted to engage the handle; the flange 21 contains an aperture 33 through which the bolt is movable, and the flange 23 contains an aperture or notch 34 into which the end of the bolt is movable.

A coiled spring 35 is disposed on the bolt 31, between a collar 36 fixed thereon and the flange 21, to retract the bolt and hold it normally out of engagement with the flange 23, the bolt being pushed forward against the action of the spring and held in engagement with the flange by a usual form of padlock 37 having a bow 38 which passes through the aperture 39 of the bolt.

The open switch blade 16 stands normally with the lug 16' thereon in engagement with the crown 11 of the yoke, in which position the blade is electrically separated from both terminals 1 and 1'. The frictional engagement between the ends of the blade and the sockets or "wipes" 17 and 17' of the terminals is broken by pulling down the handle 18, the adjustable spring 25 providing means for applying the desired force to the blade to keep it open against undesired closure. When it is desired to lock the switch blade open, to insure a continuing open circuit, the bolt 31 is locked in engagement with the flange 23.

Having described my invention, I claim:

1. In mechanism of the character described, the combination of a pair of terminals, non-conducting means connecting said terminals, a yoke connected with said means, and a fulcrumed conducting blade connected with said yoke so as to coact with said terminals and insulated by said means from said terminals, said blade when open being disengaged from both terminals and when closed engaging both terminals to electrically connect them and provide a track for a trolley.

2. In mechanism of the character described, the combination of a pair of terminals, non-conducting members connecting said terminals, a yoke having bifurcations fixed to said members, a fulcrumed conducting blade connected with said bifurcations between said members so that its ends will coact with said terminals, and a hanger connected with said yoke.

3. In mechanism of the character described, the combination with ends of trolley wire sections, of terminals having means for fixing them to the respective ends aforesaid, a pair of non-conducting bars connecting said terminals on opposite sides of the con-

nections of said sections therewith, a conducting blade for coaction with said terminals, and means whereby said blade is fulcrumed so as to oscillate in a plane between said bars and adapted to be insulated thereby from said terminals.

4. In mechanism of the character described, the combination of trolley wire sections, insulating bars, and means comprising a fulcrumed conducting member fixed to and adapted to oscillate in a plane between said bars, with a pair of terminals having sockets for engaging ends of said sections, sockets for engaging ends of said bars and means for engaging ends of said member.

5. In mechanism of the character described, the combination of trolley wire sections, insulating bars, a yoke connected with said bars intermediate their lengths, and a fulcrumed conducting member carried by said yoke and adapted to oscillate in a plane between said bars, with a pair of terminals having means for engaging ends of said sections, means for engaging ends of said bars and means for engaging ends of said member.

6. In mechanism of the character described, a pair of terminals, insulated bars connecting said terminals, a yoke having bifurcations connected with said bars, a shaft journaled in said bifurcations, a switch blade fixed to said shaft between said bifurcations for electrically connecting and disconnecting said terminals, a handle for operating said shaft, and a coiled spring on said shaft having its ends connected with said handle and yoke for holding said blade out of engagement with said terminals.

7. In mechanism of the character described, a pair of terminals, insulating means connecting said terminals, a bearing fixed to said means, a switch blade for connecting said terminals, a shaft for said blade carried by said bearing, a handle for rocking said shaft and blade, and a reciprocating bolt carried by said handle for engaging said bearing and locking said blade.

8. In mechanism of the character described, a pair of terminals, a pair of insulating bars connecting said terminals, bearings fixed to said bars in insulating relation to said terminals, a shaft journaled in said bearings, a switch blade carried by said shaft for connecting said terminals, a handle on said shaft for rocking said blade, a reciprocating bolt carried by said handle for engaging a bearing aforesaid to lock said blade, a spring for normally holding said bolt out of engagement with said bearing, and a lock for holding said bolt in engagement with said bearing.

9. In mechanism of the character described, a pair of terminals, insulating bars

connecting said terminals, a yoke having bifurcations connected with said bars, a shaft journaled in bearings in said bifurcations, a switch blade fixed on said shaft between said bars for connecting said terminals, a handle for turning said shaft, an adjustable spring connecting said handle and a bearing aforesaid for holding said blade open, a bolt car-

ried by said handle for engaging a bifurcation aforesaid to hold said blade open, a 10 spring for normally retracting said bolt and means for locking said bolt in engagement with said bifurcation.

In testimony whereof I have hereunto set my name this 26th day of September, 1916. 15

A. H. ENGLUND.
